(57) CLAIM

The ornamental design for a baseball jersey frame, as shown and described.

DESCRIPTION

FIG. 1 is a front perspective view of my ornamental design for a baseball jersey frame.

FIG. 2 is a front elevation view of the baseball jersey frame of FIG. 1.

FIG. 3 is a left side elevation view of the baseball jersey frame of FIG. 1.

FIG. 4 is a right side elevation view of the baseball jersey frame of FIG. 1.

FIG. 5 is a top plan view of the baseball jersey frame of FIG. 1; and,

FIG. 6 is a bottom plan view of the baseball jersey frame of FIG. 1.

The broken lines shown are included for the purpose of illustrating portions of the baseball jersey frame that form no part of the claimed design.

1 Claim, 4 Drawing Sheets
